K. A. SIMMON ET AL

CONTROL APPARATUS

Filed March 23, 1920

Fig. 1.

UNITED STATES PATENT OFFICE.

KARL A. SIMMON, OF EDGEWOOD PARK, AND HARRY R. MEYER, OF WILKINSBURG, PENNSYLVANIA, ASSIGNORS TO WESTINGHOUSE ELECTRIC & MANUFACTURING COMPANY, A CORPORATION OF PENNSYLVANIA.

CONTROL APPARATUS.

Application filed March 23, 1920. Serial No. 368,023.

To all whom it may concern:

Be it known that we, KARL A. SIMMON, a citizen of the United States, and a resident of Edgewood Park, in the county of Allegheny and State of Pennsylvania, and HARRY R. MEYER, a citizen of the United States, and a resident of Wilkinsburg, in the county of Allegheny and State of Pennsylvania, have invented a new and useful Improvement in Control Apparatus, of which the following is a specification.

Our invention relates to control apparatus and it has special relation to fluid-pressure-operated slidable contact members for governing the circuits of electric motors.

One object of our invention is to provide a relatively compact, effective and reliable device of the above-indicated character for effecting operation of certain electrical circuits in accordance with a predetermined time sequence.

Another object of our invention is to provide, in combination with a piston-and-cylinder device for actuating a movable contact member, auxiliary means in the form of relatively small cylinders that are connected to one end of the main cylinder to absorb a predetermined degree of fluid pressure under initial operating conditions, whereby the otherwise rapid starting movement of the contact member is prevented.

Viewed from another angle, it is an object of our invention to provide a slidable contact member that shall be actuated at a substantially constant speed by a piston-and-cylinder device, irrespective of the tendency toward an initial rush of fluid-pressure and a consequent relatively rapid initial actuation of the contact member.

Our invention may best be understood by reference to the accompanying drawing, wherein—

Figure 1 is a view, chiefly in side elevation and partially in section, of a control apparatus constructed in accordance with our present invention; and

Fig. 2 is a view, in front elevation, of the device shown in Fig. 1, with the exception of the controlling-valve means therefor.

Referring to the drawing, the structure here shown comprises a suitable base or supporting slab 1 upon which is mounted an operating piston-and-cylinder device 2, and an insulating finger-carrying bridge 3 for co-

operating with a slidable or face-plate type 55 of contact-carrying member 4, which is actuated by the main cylinder device 2 and the movement of which is directed by a suitable guiding frame 5. A plurality of auxiliary cylinders 6 and 7 are connected to the main 60 cylinder device 2, a suitable piping arrangement 9 being provided for connecting the three cylinders with an electromagnetically-controlled valve device 10 with which is associated an appliance 11 for reducing the 65 normal fluid pressure provided from a supply pipe 12. The actuation of the movable contact-carrying member 4 by means of the cylinder device 2 is opposed by a plurality of relatively long spiral springs 8, as herein- 70 after more fully set forth.

The main cylinder device 2 comprises a cylinder or tube 2^a that is supported, at its respective ends, by means of a plurality of bent straps or yokes 15 and 16 which are secured to the base 1 by means of a plurality of screws or bolts 17 and 18, respectively. A piston member 19 travels within the cylinder 2^a, being shown in its extreme operative position, and the piston rod 20 is rigidly associated with a lug or arm 21 at the remote end of the supporting member for the movable contact device 4.

The insulating bridge 3 may be of solid or composite form and is shown as comprising two spaced blocks 3^a and 3^b and a top plate or bridging member 3^c. The bridge 3 is secured, near its opposite ends, to the base 1 by means of suitable bolts 22 and 23, respectively. A plurality of control fingers 24 are secured to the insulating plate 3^c in a single row for the purpose of engaging a suitably configured contact segment 25 on the face-plate device or movable contact-carrying member 4. Suitable sheet insulating material 26 is placed over that portion of the face of the movable contact-carrying member 4 that is not occupied by the contact segment 25 to provide smooth contacting movement throughout the operating 100 range of the apparatus.

The contact segment 25 and the insulating material 26 are suitably secured to an insulating plate 27 which is mounted upon a metallic base or support 28, with which the lug or arm 21 is preferably integrally associated.

For the purpose of securing steady move-

ment of the contact-carrying member 4 in the desired plane of operation, a plurality of side guiding members or rails 29 and 30 are provided upon their inner faces with a 5 right-angle groove for receiving correspondingly-dimensioned tongues 34 of the insulating plate 27. A suitable degree of clearance, as indicated by the reference characters 35, is provided between the right-hand and the 10 left-hand edges of the plate 27, as illustrated in Fig. 2, and the guiding rails 29 and 30, while the upper edge of the insulating plate 27 abuts against a cross-tie 33 for the guide-rails when the contact-carrying member 4 15 occupies its illustrated extreme upper position. The lower ends of the guide-rails 29 and 30 are secured to the base-plate 1 by means of suitable screws or bolts 31 and 32.

The auxiliary cylinders or surplus-capacity devices 6 and 7 are located symmetrically on opposite sides of the main cylinder device 2. The two auxiliary cylinders may be of identical form and the device 6 is shown as comprising a tubular body member 25 or pipe section 36, the upper end of which is closed by a suitable cap 37, while the lower end is screwed into an elbow 39 which communicates, through a short pipe 40, with a four-way connector 41. The auxiliary cylinder 7 is similarly connected, through an elbow 43 and a short pipe 44, to the opposite side of the four-way connector 41.

The upper outlet of the four-way connector 41 connects, through a short pipe 45, 35 with a bushing 46 leading directly to the main-cylinder device 2. The opposite or lower end of the four-way connector 41 receives a pipe 47 that communicates with the valve device 10.

40 A yoke or aperture plate 50 surrounds the bushing 46, and the lower or stationary ends of the spiral springs 8 are secured to opposite sides of the yoke member. The springs extend, in parallel lines, upwardly 45 toward the other end of the apparatus, and the upper or movable ends of the springs are hooked around the grooved ends of a pin or small rod 51 that extends through the lug or arm 21 of the supporting base 28 50 for the movable contact-carrying member 4.

The electromagnetic valve device 10 may, in general, be of any well-known type and is here shown as comprising an encasing member 52 for containing a magnet coil 53 that operates upon a plunger or armature stem 54, to one end of which is secured a double-seat valve plug 55. The outlet or delivery passage 56 of the valve permanently communicates with the pipe 47 and is 60 adapted to temporarily communicate with either an exhaust port 57, when the valve is closed, or with the pressure-reducing appliance 11 when the valve occupies its illustrated open position.

65 The pressure-reducing appliance 11 may

likewise be of any suitable type and is not believed to require detailed explanation here. The particular device illustrated is fully set forth in a copending application of Karl A. Simmon, Serial No. 342,118, filed December 3, 1919.

It will be seen that we have provided a relatively compact and rugged control apparatus which may be readily mounted in any convenient location to be remotely controlled through the agency of the electromagnetic valve device 10.

The operation of our apparatus to the illustrated extreme position may be set forth as follows. Upon the energization of the 80 magnet coil 53, the valve plug 55 is actuated to its illustrated open position to admit fluid pressure from the supply pipe 12 through the appliance 11, whereby the pressure is reduced to any desired value to correspondingly regulate the operating speed of the movable contact-carrying member 4, fluid pressure being conducted out of the valve device 10 through passage 56 and pipe 47 to the four-way connector 41.

90 The compressed fluid is then divided into three parts, the main body passing directly on to the main cylinder device 2, whereas two smaller and equal portions respectively pass into the auxiliary cylinders or tubes 6 and 7. In this way, a sufficient amount of the compressed fluid or degree of pressure thereof is absorbed in the auxiliary cylinders 6 and 7 to prevent the otherwise relatively rapid movement of the piston 19 that would 100 occur upon the sudden admission of the full amount of fluid pressure.

The piston 19 is thus gradually actuated from the lower end of the cylinder 2 toward 105 its illustrated position in the upper end, in opposition to the action of the pair of spiral springs 8. After the first rush of fluid pressure which fills the auxiliary cylinders 6 and 7 and initially actuates the piston 19, the full value of fluid pressure that is admitted through the valve device 10 is conveyed to the cylinder 2 to force the piston upwardly.

110 As a result, the movement of the face-plate device 4 under the insulating bridge 3 occurs at a substantially constant rate, and the several positions on the contact segment 25, whereby various combinations of the control fingers 24 are actively employed, may be laid out in accordance with 115 this rate of movement to effect closure of the several motor-controlling switches in the desired sequence and at proper time intervals.

120 To effect a return of the control apparatus to its normal or lower position, the magnet coil 53 may be de-energized, whereupon the plug valve 55 is actuated to its closed position to cut off access with the supply pipe 12 and to effect communication be- 125

tween the delivery passage 56 and the exhaust port 57.

Consequently, the main cylinder 2^a and also the auxiliary cylinders 6 and 7 are directly connected to the atmosphere, and a rapid exhaust of the fluid pressure in the three cylinders occurs. At the same time, the spiral springs 8 act upon the movable contact-carrying member 4 to cause it to pass underneath the bridge 3 to its lower-most position as the fluid pressure is exhausted from the main cylinder 2^a, until the arm 21 strikes the upper end of the cylinder 2^a, which marks the extreme lower position 15 of the movable contact-carrying member 4.

We do not wish to be restricted to the specific structural details or arrangement of parts herein set forth, as various modifications thereof may be effected within the spirit and scope of our invention. We desire, therefore, that only such limitations shall be imposed as are indicated in the appended claims.

25 We claim as our invention:

1. Control apparatus comprising a movable contact member, a piston-and-cylinder device for actuating said member, a base member for supporting said device, a supply-pipe for said cylinder fitted with a four-way connector, and a plurality of auxiliary cylinders located on opposite sides of the cylinder device and supported solely by said connector.

35 2. Control apparatus comprising a base member, a piston-and-cylinder device and an insulating bridge secured to opposite sides thereof, a contact member actuated by the piston to pass under said bridge, and auxiliary fluid-receiving means connected to said device.

40 3. Control apparatus comprising a base member, a piston-and-cylinder device and an insulating bridge secured to opposite sides thereof, a contact member actuated by the piston to pass under said bridge, a plurality of control fingers mounted on said bridge to engage the contact member, a plurality of springs arranged on opposite sides 45 of said device to oppose the action of the piston, and an auxiliary receptacle connected to the cylinder.

50 4. Control apparatus comprising a base member, a piston-and-cylinder device se-

cured thereto, a movable contact-carrying member having its remote end secured to the piston, guiding means for said movable member secured to said base member, and a plurality of auxiliary cylinders communicating with said device.

5. Control apparatus comprising a base member, a piston-and-cylinder device secured thereto, a slidable contact-carrying member having its remote end secured to the piston, a plurality of guiding rails for said slidable member secured to said base member, a plurality of springs secured to said remote end to oppose the action of the piston, a supply-pipe for the cylinder fitted with a four-way connector, and a plurality 65 of auxiliary cylinders communicating with said connector.

6. Control apparatus comprising a base member, a piston-and-cylinder device and an insulating bridge secured to opposite sides thereof, a slidable contact-carrying member adapted to pass under said bridge and having its remote end secured to the piston, a plurality of guiding rails for said slidable member secured to said base member, a plurality of control fingers mounted on said bridge to engage the contact member, and a plurality of auxiliary cylinders communicating with said device.

7. Control apparatus comprising a base member, a piston-and-cylinder device and an insulating bridge secured to opposite sides thereof, a slidable contact-carrying member adapted to pass under said bridge and having its remote end secured to the piston, a plurality of guiding rails for said slidable member secured to said base member, a plurality of control fingers mounted on said bridge to engage the contact member, a plurality of springs arranged on opposite sides of said device and secured to said remote end to oppose the action of the piston, a supply-pipe for the cylinder fitted with a four-way connector, and a plurality 90 of auxiliary cylinders located on opposite sides of the cylinder device and supported solely by said connector.

In testimony whereof we have hereunto subscribed our names this 10th day of March, 1920.

KARL A. SIMMON.
HARRY R. MEYER.
